ATTORNEY

UNITED STATES PATENT OFFICE.

FRANK C. HINCKLEY, OF STRATFORD, CONNECTICUT, ASSIGNOR TO COLUMBIA PHONOGRAPH COMPANY, INC., OF BRIDGEPORT, CONNECTICUT, A CORPORATION OF NEW YORK.

SOUND AMPLIFIER.

Application filed June 27, 1927. Serial No. 201,682.

This invention relates to new and useful improvements in sound amplifiers, or amplifying systems, and has particular reference to that type of amplifier for use in sound 5 reproducing machines, such as phonographs, talking machines, loud speaking telephones and radio receiving apparatus.

An object of the invention is to provide a means which will more accurately amplify 10 the sounds passed therethrough.

Another object of the invention is to provide an amplifier of the type indicated, which may be constructed with a phonograph cabinet to form a part thereof, or which may be 15 constructed as a unit separate therefrom and secured therein.

A further object of the invention is to provide a two-way horn, comprising an upper main horn and a lower main horn, of substantially equal dimensions, the sound being divided before it enters these two horns and part going to each.

A still further object of the invention is to provide an amplifier, including a tone chamber, a dividing means and a pair of horns, the dividing means including means whereby each of the horns is fed substantially the same proportion of the sound to be amplified.

Additional objects and advantages will be 30 apparent from a consideration of the following description taken in connection with the accompanying drawings, wherein:

Fig. 1 is a front elevation of a cabinet equipped with the improved amplifier;

Fig. 2 is a side view of a cabinet, looking from the right of Fig. 1, the side wall being removed;

Fig. 3 is a horizontal sectional view on the line 3—3 of Fig. 1; and

Fig. 4 is a fragmentary sectional view on the line 4—4 of Fig. 2.

Referring in detail to the drawings,—the sound to be amplified is delivered from the tone-arm, or its equivalent (not shown) to a 45 conduit, or coupling member 5, which may be made of die cast metal, preferably aluminum. On leaving the coupling member 5, the sound enters the tone chamber 6 from whence it is delivered to a dividing means 7.

Tone chamber 6 is made entirely of wood, and comprises two diverging side walls 8 and 9 respectively, a rectangularly-shaped front wall 10 and a rear wall 11. The rear

wall 11 also forms the back of the dividing means 7 and the back of the cabinet. On 55 leaving the tone chamber 6, the sound enters into the dividing means 7.

The dividing means 7 comprises a bottom 12, a pair of short top boards 13 and 14 respectively, arranged to have their opposed 60 edges in engagement with the lower edges of the diverging walls 8 and 9, and a pair of end blocks 15 and 16 respectively. These end blocks space the top and bottom boards apart 65 and have their inner surfaces curved, as best shown in Fig. 3, for reasons which will be obvious. The front central portion of the dividing means is closed by means of a board 17, while its back is closed by the board 11, as above described.

Arranged centrally within the dividing means, and extending transversely thereof, is a wedged shaped dividing block 18, which divides the sound into two columns. This dividing block causes the sound delivered to the 70 dividing means to pass in substantially equal amounts to the lateral passages 19 and 20, to be discharged through the exit openings 21 and 22 at the respective ends of board 17.

It is to be noted particularly that the dividing means is arranged horizontally, and is in the form of a rectangle. Further, it will be noted that the two exit openings 21 and 22 are in the same plane, both horizontally and vertically. The area of the bottom opening 85 of the tone chamber equals the combined cross-sectional area of the lateral passages 19 and 20 respectively, which are disposed within the dividing means.

When the sound is discharged through exit 90 openings 21 and 22, it is delivered or directed into a pair of horns, comprising an upper main horn 23 and a lower main horn 24. These horns are diagonally disposed with relation to each other.

Upper main horn 23 is made up of sections, and includes an upwardly inclined top wall 25 and a vertically flaring inner wall 26, which increases in height towards its discharge end. The bottom of the upper main horn is formed 100 by a board 27, which along one edge contacts with the side wall 28 of the cabinet, and whose other edge is inclined and contacts with the wall 26 of the horn, as best shown in Fig. 3. This board extends from the lower edge of the 105 exit opening 21 to the forward edge of the

cabinet, and as is readily apparent from an inspection of Fig. 1 the board slopes upwardly so that its forward edge is in a plane with the horizontal center of the dividing means 7. 5 As will be readily apparent from a study of the drawings, this board 27 separates the main upper horn from the main lower horn. The vertical board 28 forms the outside wall of the upper main horn, and also may form the 10 outside wall of the cabinet, or other housing means.

Board 27, which as stated above, forms a dividing means between the upper horn and the lower horn, also forms a part of the top 15 wall of the lower horn. There are also two angularly disposed boards 29 and 30, which form the remainder of the top wall of the lower horn. Occasion for the use of these boards results from the fact that the exit 20 openings 21 and 22 are in the same plane, and that the horns 23 and 24 incline upwardly. The outer end portion of the vertically flared 25 inner wall 26 of the top horn 23 forms a dividing line, or partition, between that portion of the top wall of the lower horn, which is also the bottom of the upper horn, and these two angularly disposed boards. Board 29 is in 30 the shape of a triangle, and is larger in area than board 30, which might also be said to be in the form of a triangle. These boards slope downwardly from the upper edge of the exit opening 22 towards the front or discharge end of the lower horn and terminate in a plane with the horizontal center of said opening.

35 An inclined wall 31, which flares outwardly at the discharge end of the horn, forms the inner wall of the lower horn, while an inclined upwardly sloping wall 32 forms the bottom of the lower horn. Vertical wall 33 40 forms the outside wall of the lower main horn, and this wall also forms one wall of the cabinet, or other housing means.

Board 31 along its upper edge inclines from its front edge downwardly for a distance and 45 then inclines upwardly. The downwardly inclined portion of the edge contacts with the under side of partition 27, while the upwardly inclined edge is engaged by one edge portion of the triangular board 29. Through the 50 use of the triangular boards 29 and 30, and the double inclined edge of board 31, a full open throat is provided for the lower horn.

55 For acoustical reasons, I have found it desirable to construct my horns in the manner above stated, as a more faithful amplification of the original sounds is obtained.

While I have shown and described preferred and satisfactory embodiments of the 60 invention, it will be understood that the disclosure is entirely by way of illustration and is not for the purpose of limitation. Various modifications of the invention, within the scope of the appended claims, will readily suggest themselves to those skilled in the art. 65 Therefore, the invention not being limited to

the disclosure, reference must be had to the appended claims for a definition of the limitations of the invention.

What is claimed is:

1. In a sound amplifier, a tone chamber, a 70 dividing means, said tone chamber adapted to deliver sound to said dividing means, said dividing means comprising a pair of lateral passages, a dividing block directing sound into each of said passages, an upper main horn, a lower main horn, said dividing means delivering sound to each of said horns, and said horns being diagonally disposed with relation to each other.

2. An amplifier, including a box-like 80 dividing means having an exit opening in its front wall adjacent each of its ends, said exit openings being in the same plane both horizontally and vertically, and a pair of horns arranged one above the other and each 85 of said horns being fed from one of said exit openings.

3. In an amplifying means, a dividing 90 means comprising a rectangular box-like structure having a dividing block and a pair of lateral passages, said amplifier having an exit opening in its front wall at the end of each of said passages, said passages being in the same horizontal plane, and a pair of superimposed horns receiving sound from 95 said passages.

4. An amplifier, comprising a dividing 100 means having a spaced pair of exits arranged in the same horizontal plane, a pair of horns each receiving sound from one of said exits, said horns being arranged one above the other, the bottom of the upper horn inclining upwardly and forming a part of the top of 105 said lower horn.

5. In an amplifier, a dividing means, said 110 dividing means comprising a rectangular box-like body having an opening in its forward side adjacent each of its ends, a pair of lateral passages in said dividing means, one terminating at each of said exit openings, a 115 wedged-shaped dividing block for directing sound to be amplified into each of said passages, and a pair of blocks one adjacent each of said exit openings, each of said blocks having a curved surface for deflecting the sound from the lateral passages through the exit openings.

6. An amplifier, including a box-like 120 dividing means having an exit opening in its front wall adjacent each of its ends, said exit openings being in the same plane both horizontally and vertically, a pair of horns arranged one above the other and each of said horns being fed from one of said exits, and the bottom of the upper horn forming a part 125 of the top of the lower horn.

7. An amplifier, including a box-like dividing 130 means having an exit opening in its front wall adjacent each of its ends, said exit openings being in the same plane both horizontal-

- ly and vertically, a pair of horns arranged one above the other, and each of said horns being fed from one of said exits, the bottom of the upper horn being inclined upwardly and forming a part of the top of the lower horn. 15
- 5 and forming a part of the top of the lower horn, and that portion of the top of the lower horn adjacent the opening with which said lower horn is connected, inclining downwardly.
- 10 8. An amplifier comprising a pair of horns arranged one above the other, said horns being diagonally disposed with relation to each
- other, and the bottom of the upper horn inclined upwardly and forming a part of the top of the lower horn. 15
9. An amplifier comprising a pair of horns arranged one above the other, said horns being diagonally disposed with relation to each other, and the bottom of the upper horn forming a part of the top of the lower horn. 20

Signed at Bridgeport, in the county of Fairfield, and State of Connecticut, this 22nd day of June, A. D. 1927.

FRANK C. HINCKLEY.
